UNITED STATES PATENT OFFICE

ALBERT EDGAR BLACKMAN, OF MOUNT VERNON, NEW YORK

CABINET

Application filed June 5, 1928. Serial No. 283,030.

My present invention relates to wall cabinets having mirror-equipped doors. The purpose of my invention is to provide an article of the class described of improved, 5 simple and durable construction; and particularly to provide a cabinet wherein the mirror-equipped door may be moved forwardly and laterally upon a wide and relatively long pivoting bracket so that the door may face forwardly when the door is wide open, or it may face to any forwardly inclined angle when the bracket is swung part way open.

Another object is to provide a construction in a cabinet of the type mentioned where the pivoting bracket is very strong and effective but is so attached to or combined with the body of the cabinet and with the door as to be practically out of sight when the cabinet is opened and so that most of it is concealed when the door is closed. Further purposes and advantages of the cabinet will appear from the specification and claims herein. A further purpose is to provide a cabinet of the type indicated having a mirror-equipped door mounted upon the cabinet with a long pivoting bracket of such construction and arrangement that the door may be opened as an ordinary door without relative movement between the door and the bracket or may be opened by pivotal movement at both ends of the bracket allowing the mirror to still face forwardly.

Fig. 1 is an isometric projection of one form of cabinet embodying this invention. Fig. 2 is a similar projection of said cabinet with the door swung entirely open and with the mirror facing forwardly. Fig. 3 is a horizontal sectional view on line 3-3 of Fig. 2. Figs. 4 and 4^a are similar views on a somewhat enlarged scale of said cabinet on line 4-4 of Fig. 1. Fig. 5 is an isometric projection of a modified form of the cabinet as seen from the rear with the door swung half-way open and parallel with the front of the cabinet.

Fig. 6 is a front view of an upper corner of the cabinet shown in Fig. 5 with the door open but with the mirror unexposed or faced

rearwardly. Fig. 7 is a horizontal sectional view of a modified form.

Referring to the drawings and first to the form of cabinet shown in Figs. 1 to 4^a, it will be seen that the cabinet consists of a casing 55 or body 7, a door 8 which carries in its forward face the mirror 9 with said door connected to the casing by supporting bracket 10 which is pivotally connected at its outer end to the inner side of the door and at its inner end is also pivotally connected to the casing on the outside thereof on one of its vertically extending sides.

The casing 7 is formed in conventional manner of sheet metal so that said casing has 65 opposite vertical sides 11 and 12, a top 13, a back 14, and a bottom 15. In the case there is usually mounted one or more shelves 16. The front of the casing has a large opening 17 extending for substantially the entire 70 front of the casing.

The door 8 is conveniently formed of two flanged plates of sheet metal, the inner one 18 forming a back for the mirror 9, the face of which is exposed through the large opening 75 made for that purpose in the outer plate 19 of the cover. The flange 20 of the inner plate fits within the flange 21 of the outer plate and by fastening these two flanges together in any conventional manner the door is held 80 in assembled condition.

Near the vertical median line of the door and upon the inner face thereof there are provided and secured two spaced looped straps 22, the looped portion of these straps 85 forming a vertical bearing in which is mounted the vertical rod 23. The over-lapping portions 24 of each strap 22 are adjustably drawn together by the nut 25 on the bolt 26 which conveniently forms the means 90 also for securing the said straps to the back plate of the door.

Near the front outer edge of one vertical side, say the right-hand side 12 of the case, there is provided a pair of looped straps 27 95 substantially similar to the straps 22 and each fastened to the casing by a bolt 28. Preferably the head of this bolt bears against the outer portion 29 of the strap 27, and then the shank of the bolt extends through the inner 100

strap portion 30 and then through the casing side 12. The over-lapping parts 29 and 30 of the hinge strap 27 may thus be drawn together by means of the nut 31 on said bolt 5 within the casing so as to get an adjustable tension of the said strap against the bearing rod 32 placed in said strap.

The supporting bracket 10, as particularly appears in Figs. 3 and 4, is L-shaped in horizontal section. The base or shorter arm 33, has its inner vertical edge rigidly mounted upon the bearing rod 32 as by the metal of said bracket being wrapped or rolled about said rod. The other and longer arm 34 of the L-shaped bracket has its outer end similarly mounted upon the bearing rod 23 secured as above mentioned in the straps 22 upon the cover.

When the door is closed the supporting bracket 10 as appears in Fig. 4, will have its longer arm 34 housed within the case of the cover on a line close to the back plate of the cover. The other or short arm 33 of the bracket will lie close against the outer face of 25 the side 12 and most of this arm will be between said side 12 and the rearwardly extending flanges 20 and 21 of the cover.

In other words, the cover 8 has its flanges on the right hand side of the door over-lap the 30 short arm 33 of the supporting bracket 10 and also over-lapping the forwardly extending portions of the straps 27 secured to the outer face of the side 12 near its top and bottom respectively.

Accordingly when the cover is closed, only the loop part of the straps 27 and only the part of the supporting bracket 10 that is wrapped around the inner bearing-rod 32 will be visible from the outside of the cabinet.

The relative position of the parts when the cover is opened is plainly seen in Fig. 3, and it will be noted particularly that the supporting bracket and both pairs of hinge straps are out of sight when one looks at the front of the 45 cabinet and the mirror equipped door.

Preferably the opposite vertical edges of the supporting bracket 10 will be clamped rigidly against the respective bearing-rods 23 and 32 and the pivotal movement will take place between these rods and the respective hinge straps 22 and 27. The tension of these straps against the bearing rods may be adjusted by the nuts 25 and 31 already mentioned, so as to cause the cover to stay at any position to which it is moved but still allowing the cover to be moved with convenience when desired.

In the construction shown in Fig. 5, there is used the mirror-equipped door and the L-shaped supporting bracket pivotally connected by bearing rods and hinge straps as already described with the outer set of straps 22 on the inner face of the cover and with the inner or casing set of straps 27 on the outside of the 65 casing. In this construction, however, the

casing has a front flange 35 extending laterally outward from the two sides 11 and 12 of the casing and from the top 13 and the bottom 15 of the casing. From the outer edge of this front flange 35 there extends a rearwardly extending flange 36 parallel to the adjacent sides, top and bottom of the casing but spaced therefrom. This box-like construction is particularly convenient when the cabinet is to be set into a recess in the wall and the front flange 35 and side flanges 36 serve to cover the edges of the recess in the wall and give a finished appearance to the cabinet when in place.

The hinge straps 27 in this construction shown in Figs. 5 and 6 are secured to the rearwardly extending flange 36 upon the casing. The door when closed over-laps the front flange 35 and extends part way back upon the side flanges 36. The flange upon the door also over-laps the short arm 33 of the supporting bracket when the door is closed, as already described with regard to the construction shown in Figs. 1 to 4^a.

In any form of my invention the supporting bracket and the hinge straps 22 upon the inner side of the door are of such size or length vertically and so arranged that the total height of the supporting bracket and the said hinged straps is less than the height of the opening of the cabinet so that the said hinge straps and the adjacent part of the supporting bracket will enter the opening when the door is closed and allow the door to close flush against the front of the cabinet. In the cabinet shown in Figs. 1 to 4^a this is accomplished by spacing the upper hinge straps slightly down from the top of the door and the lower hinged strap slightly up from the bottom of the door, but in the form shown in Figs. 5 and 6 where there is an appreciable width due to the front flange 35 the hinge straps have to be spaced farther from the top and bottom flanges of the cover and the height of the supporting bracket reduced accordingly.

A cabinet embodying this present invention has the particular advantage that the door can be opened like an ordinary door by the swinging action taking place entirely at the hinge straps 27 upon the casing, and without there being any relative movement between the door 8 and the supporting bracket 10. This operation of the door is plainly indicated in the position of the door and supporting bracket in Fig. 4^a.

The ability of this construction to hinge as an ordinary door comes from the fact that the inner pivoting edge of the supporting bracket is secured to the casing outside of the casing. For this reason no cramping of the door relative to the supporting bracket nor of the supporting bracket relative to the casing takes place when the left side of the door, as the parts are seen in

Fig. 4, is swung forwardly. This action is further facilitated by having convenient friction fastening means between the arm 33 of the bracket and the adjacent flange of the door.

Such fastening means may consist of interengaging bosses 40 on the bracket and shallow recesses 41 upon the adjacent flange of the door. Preferably also suitable flange fastening devices such as bosses 42 upon the casing near the front edge of the left side 11 are provided to engage shallow recesses 43 oppositely located upon the left-hand flange of the door 8.

It will be particularly noticed that the simple hinging action just mentioned of swinging the door open by moving the door and the supporting bracket together as a unit relative to the casing does not interfere with the regular swiveling or double-hinging motion of the door relative to the supporting bracket and of the supporting bracket relative to the casing which takes place when the door is opened as shown in either Figs. 2, 3 or 5, with the mirror of the door still facing forwardly. Similarly it will be noticed that the said swiveling or double-hinged motion is not in any way hindered or interfered with by the device being capable of the single hinged motion such as shown in full lines in Fig. 4.

The particular form of the supporting bracket and of its mounting upon the door and the casing provide very simple and efficient means for allowing the door to have either the single hinged motion or the double hinged motion. It will be especially noticed that the construction here shown for obtaining the said two types of door motion is attained with the very simplest forms of cabinet and door, so that the article can be made and assembled economically and will be durable in use and not liable to get out of repair. Neither the casing nor the door has any special addition or modification nor portion thereof cut away.

In the forms of my invention shown in Figs. 1 to 6 inclusive and heretofore described in detail the supporting bracket is L-shaped in horizontal section and the short arm 33 of the bracket has a spring-tensioned or frictional engagement with the rearwardly projecting flanges upon the door. Fig. 7, however, shows a modified form of my invention that is still within the scope of several of the claims. In this modified form the short arm 53 of the L-shaped supporting bracket 54 instead of facing rearwardly when the door is closed faces forwardly and engages the outer edge 55 of the door 56. In Fig. 7 the casing is illustrated as being of the same type as shown in Figs. 5 and 6 with a front flange 35 and a rearwardly extending flange 36. The door 56, however, sets back into the opening of the casing and illustrates my in-

vention as applied where it is desired to have the door set more or less into the opening of the casing or as usual in such cases to have the front of the door flush with the front of the casing. The casing end of the supporting bracket 57 is secured to the casing by turning the free edge of the short arm 53 about pivot rod 58 mounted at its upper and lower ends in straps 59 secured to the casing. The door end of the long arm 57 similarly 75 has its edge turned about a pivot rod 60 supported at its upper and lower ends by hinge straps 61 similar to the straps 22 already described.

Upon the opposing faces of the short arm 53 of the bracket and the opposite edge 55 of the door are provided oppositely located projecting bosses 61 and recesses 62 as already described with regard to previous forms and operating to make still more secure the spring 85 tension or frictional engagement between these two parts, namely the edge of the door and the short arm of the bracket. With these two parts thus normally held together the door of the cabinet shown in Fig. 7 can be 90 swung open by grasping the knob 63 at the left side and swinging the door and the bracket as a unit open by pivotal action of the rod 58 in its straps 59. If, however, it is desired to have the cabinet function with its 95 double swivel action the knob 64 at the right hand side of the door is pulled sharply forward thus separating the bosses 61 from the recesses 62.

It will now be seen that in either form of 100 this invention the supporting bracket when seen in horizontal section comprises an L-shaped portion or a right angle portion having a long arm secured at its outer end to the inside of the door and a short arm opposite one vertical edge of the door and that the short arm portion of the bracket when the door is closed detachably engages preferably with friction or spring tension a portion of the door at right angles to the main plane 110 of the door. In other words, the angle bracket makes a detachable clamping action upon a forwardly and rearwardly extending part of the door at or near its edge. In the form of the invention shown in Figs. 1 to 6 the 115 short arm of the bracket presses outwardly against the inner side of a rearwardly extending flange at the side of the door. In the form of the invention shown in Fig. 7 the short arm of the bracket bears inwardly 120 against the main outer edge of the door and is detachable therefrom. The spring or frictional engagement is in each case emphasized by opposing bosses and recess already described. This L-shaped form of the bracket 125 or the making of the bracket to include an L-shaped portion provides two closely swinging faces wherein by relatively small bosses and depressions a good frictional or spring tensioned detachable fastening means may be 130

provided without extra parts and with little extra labor in the manufacture with the inner end of the bracket and its adjacent edge of the door thus securely but detachably connected. The cabinet can be operated as desired either with its full swivel or double hinged motion as shown in Figs. 1 and 2 or with the ordinary swinging motion on one pivot as shown in Fig. 4^a.

10 What I claim as new and desire to secure by Letters Patent, is:

1. In a wall cabinet the combination of a casing having a front opening, a door therefor having a mirror mounted in its outer face and having a vertical edge face extending inwardly perpendicularly to the general plane of the door and a supporting bracket of resilient sheet metal having in horizontal section an L-shaped portion which is pivotally connected at the outer end of its long arm to the inner side of the door intermediate its vertical edges, said bracket being pivotally connected at its inner end to the outside of the casing whereby when the door is shut the long arm of the L-shaped portion lies close to the inside of the door and the short arm of said L-shaped portion by spring action relative to the long arm detachably engages the said inwardly extending face of the door.

2. In a wall cabinet the combination of a casing having a front opening, a door there-through having a mirror mounted in its outer face, said door having adjacent one vertical edge a surface at right angles with the general plane of the door and a supporting bracket of resilient sheet metal having in horizontal section an L-shaped portion, the outer end of the long arm of said L-shaped portion being pivotally connected to the inner side of the door intermediate its vertical edges and the inner end of the bracket pivotally connected to the outside of the casing with the short arm portion of the said bracket adapted by spring action relative to the long arm to detachably engage the said surface of the door, that is at right angles to the plane of the door and form therewith a spring catch whereby through pivotal action at both ends of said bracket and by disengaging said spring catch the door may be swung forwardly and laterally away from the front opening with the mirror facing forwardly or through pivotal action at only the inner end of the bracket and leaving the spring catch engaged, the door may be swung open without relative movement between the bracket and the door.

3. In a wall cabinet the combination of a casing having a front opening, a door therefor having a mirror mounted in its outer face, said door having at one vertical edge a face extending inwardly perpendicularly to the general plane of the door and a long vertically-extending supporting bracket of resilient sheet metal having in horizontal sec-

tion an L-shaped portion which is pivotally connected at the outer end of its long arm to the inner side of the door near its vertical median line, said bracket being pivotally connected at its inner end to the outside of the casing whereby when the door is shut the long arm of the L-shaped portion lies close to the inside of the door and the short arm of said L-shaped portion is adapted by spring action relative to the long arm to detachably engage the said inwardly extending face of the door whereby through pivotal action at both ends of said bracket the door may be swung forwardly and laterally away from the front opening with the mirror facing forwardly or through pivotal action at only the inner end of the bracket the door may be swung open without relative movement between the bracket and the door.

4. In a wall cabinet the combination of a casing having a front opening, a door there-through having a mirror mounted in its outer face, said door having adjacent one vertical edge a surface at right angles with the general plane of the door and a long vertically-extending supporting bracket of resilient sheet metal having in horizontal section an L-shaped portion, the outer end of the long arm of said L-shaped portion being pivotally connected to the inner side of the door near its vertical median line and the inner end of the bracket pivotally connected to the outside of the casing with the short arm portion of the said bracket adapted by spring action relative to the long arm to detachably engage the said surface of the door, that is at right angles to the plane of the door and form therewith a spring catch whereby through pivotal action at both ends of said bracket and by disengaging said spring catch the door may be swung forwardly and laterally away from the front opening with the mirror facing forwardly or through pivotal action at only the inner end of the bracket and leaving said spring catch engaged the door may be swung open without relative movement between the bracket and the door.

In witness whereof I have affixed my signature, this 22 day of May, 1928.

ALBERT EDGAR BLACKMAN.
